UNITED STATES PATENT OFFICE.

ABRAHAM HAAS AND EDGAR BARUCH, OF SAN FRANCISCO, CALIFORNIA.

RAW-WOOL-WASHING APPARATUS.

SPECIFICATION forming part of Letters Patent No. 729,333, dated May 26, 1903.

Application filed July 30, 1902. Serial No. 117,646. (No model.)

To all whom it may concern:

Be it known that we, ABRAHAM HAAS and EDGAR BARUCH, citizens of the United States, and residents of San Francisco, in the county of San Francisco and State of California, have invented a new and Improved Raw-Wool-Washing Apparatus, of which the following is a full, clear, and exact description.

The invention relates to apparatus for washing raw sheep's wool and similar fibers, and its object is to provide a new and improved raw-wool-washing apparatus which is simple and durable in construction, very effective in operation, easily manipulated, and arranged to permit its use in local wool-growing centers, to allow of washing or cleansing raw sheep's wool and other textile fibers without the use of elaborate plants or machinery, and to remove the natural greases, fats, dirt, and other extraneous matter from the fibers, and to convert the by-products into merchantable materials.

The invention consists of novel features and parts and combinations of the same, as will be more fully described hereinafter and then pointed out in the claims.

A practical embodiment of the invention is represented in the accompanying drawings, forming a part of this specification, in which similar characters of reference indicate corresponding parts in both views.

Figure 1 is a front elevation of the improvement, parts being shown in section; and Fig. 2 is a side elevation of the same.

35 The improved apparatus is mounted on a suitably-constructed frame A, which supports an extractor B, preferably in the form of a cylinder closed at the lower end and provided at its upper end with a removable cover B' for introducing or removing a wire cage C, containing the raw sheep's wool or like fiber D to be treated.

The upper end of the extractor B is connected by a pipe E, having a valve E', with the lower end of a reservoir F, for containing 45 benzine or a similar hydrocarbon cleansing compound for dissolving the fats and greases contained in the raw sheep's wool held in the cage C, inserted in the extractor B. The bottom of the latter is connected by a pipe G, having a valve G, with a caldron H, in the

shape of a closed vessel, containing in its bottom a steam heating-coil I, having one outer end I' provided with a valve I² and connected with a steam-supply pipe J, leading from a 55 boiler or similar source of steam-supply. A branch steam-pipe K leads from the supply-pipe J into the lower end of the extractor B, and the said steam branch pipe K is provided with a valve K', normally in a closed position. 60

From the top of the caldron H leads a pipe L, connected at its upper end with a condenser N in the shape of a plurality of coils extending within a water-tank O, through which passes water or other cooling medium 65 supplied by a pipe O' and carried off by a discharge-pipe O². The lower end of the condenser N terminates in a pipe N', connected with the upper end of the reservoir F, which latter is provided at its bottom with a 70 gage F' for determining the presence of water of condensation, as hereinafter more fully described, and the said reservoir F is also provided with a gage-glass F² for indicating the level of the liquid contained in the reservoir F. The upper end of the extractor B is connected by a pipe P, having a valve P', with the pipe L, leading to the condenser N. The caldron H is provided with a charging-funnel Q, having a valve Q'. 75

80 The operation is as follows: The raw sheep's wool or similar fiber is placed into the cage C, and then the latter, with the wool, is introduced into the extractor B, after which the cover B' thereof is closed and the valve E' is then opened to allow the benzine to flow by its own gravity from the overhead reservoir F through the pipe E into the extractor B in contact with the wool, so as to dissolve fats and greases adhering to the wool fibers 85 and at the same time loosen dirt and other impurities. The liquid benzine percolates through the wool and finally passes through the pipe G into the caldron H, carrying with it the dissolved fats and greases as well as 90 other impurities.

In the caldron H the benzine is separated 95 from the fats, greases, dirt, and other extraneous matter by heat emanating from the coil I, which heat evaporates the benzine, and the vapors now pass from the caldron H up through the pipe L into the condenser N, in

which the benzin vapors are converted back into liquid form, passing by the pipe N' into the reservoir F to be reused in the extractor B, in the manner above described. This 5 operation is continued until the greases and fats of the wool have been completely dissolved and removed from the extractor.

As shown in the drawings, the caldron II is located below the extractor B, so that the 10 liquid benzin and the substances dissolved therein flow by gravity from the extractor into the caldron whenever the valve G' is opened. If desired, the valve G' may be closed and the liquid benzin containing the 15 dissolved fats and greases may be siphoned from the extractor B, and for this purpose a self-starting siphon G² is provided, connected at its short leg with the pipe G and at its long leg with the caldron II, the said long 20 leg having a valve G³, which may be closed whenever desired.

The pipe G is provided with a test-cock G⁴ to indicate the condition of the benzin and the substances dissolved therein—that is, 25 when the benzin shows comparatively clear at the test-cock, then the fats and greases have been removed from the wool and carried to the caldron II. When this has been done, then the valves I², G', G³, and E' are closed 30 and the valve K' in the pipe K and the valve P' in the pipe P are now opened, so that steam passes from the supply-pipe J through the pipe K into the lower end of the extractor B and through the wool contained therein, so 35 that any benzin adhering to the wool, cage C, or wall of the extractor B is vaporized and carried with the steam by way of the pipes P and L to the condenser N to be condensed therein. The water of condensation flowing 40 by the pipe N' into the reservoir F readily separates from the benzin, and this water can now be drawn off through the gage-cock F', which also indicates when the water has been completely withdrawn from the reservoir 45 and the latter only contains benzin. When the benzin has been expelled from the extractor B, as described, then the valves K' and P' are closed and the cover B' is then opened and the cage C, with the cleansed wool, 50 is removed, and the cage is refilled with raw clipped wool and again inserted in the extractor B. The above-described operation is then repeated—that is, the valves E', G', and I² are opened to subject the wool in the extractor 55 to the action of the liquid benzin to allow the benzin and the fats and greases dissolved by it to pass to the caldron II, in which the

benzin is vaporized and separated from the fats and greases and other extraneous matter, as above explained.

The bottom of the caldron II is provided with a discharge-faucet H' for discharging the fats, oils, and other impurities from the caldron II whenever it is desired to do so.

From the foregoing it will be seen that the 65 benzin employed is used over and over again, so as to permit of cleansing the wool at a comparatively low cost.

Having thus described our invention, we claim as new and desire to secure by Letters 70 Patent—

1. In an apparatus of the class described, the combination of a main frame, an extractor mounted centrally thereof, a cage for containing the material to be treated and adapted 75 to be inserted in said extractor, a reservoir situated above said extractor and connected therewith, said reservoir supplying benzin to the extractor, a caldron below said extractor, means for siphoning the benzin from the 80 extractor to the caldron, a heating-coil in said caldron, a condenser above the reservoir communicating with the caldron and said reservoir, and means for introducing a charge of steam upward through the material in the ex- 85 tractor, as set forth.

2. In an apparatus of the class described, the combination of a main frame, an extractor provided with a cage for the material, mounted centrally of said frame, a reservoir 90 for a liquid cleansing compound mounted above and connected with said extractor, a caldron provided with a heating-coil mounted beneath the extractor, a pipe leading from the bottom of said extractor, a self-starting 95 siphon having a short leg connected with said pipe and its long leg with the caldron, a valve for said siphon, a reservoir mounted above the extractor, a condenser above the reservoir, said condenser communicating with the cal- 100 dron, the vapor passing from the caldron being liquefied in the condenser, means for drawing off the water from the condenser, and means for conveying the liquid cleansing compound from the condenser to the reservoir, substan- 105 tially as set forth.

In testimony whereof we have signed our names to this specification in the presence of two subscribing witnesses.

ABRAHAM HAAS.
EDGAR BARUCH.
